(57) **CLAIM**

The ornamental design for a transfer pump, as shown and described.

DESCRIPTION

FIG. 1 is a first isometric view of a transfer pump; FIG. 2 is a second isometric view of the transfer pump; FIG. 3 is a third isometric view of the transfer pump; FIG. 4 is a fourth isometric view of the transfer pump; FIG. 5 is a front elevational view of the transfer pump; FIG. 6 is a left side view of the transfer pump; FIG. 7 is a right side view of the transfer pump; FIG. 8 is a rear elevational view of the transfer pump; and FIG. 9 is a top plan view of the transfer pump; and, FIG. 10 is a bottom plan view of the transfer pump. The broken lines in the Figures represent portions of the transfer pump and form no part of the claimed design.

1 Claim, 10 Drawing Sheets
